CLAIM

The ornamental design for a projector, as shown and described.

DESCRIPTION

FIG. 1 is a top front perspective view of the projector.

FIG. 2 is a front view of FIG. 1 thereof.

FIG. 3 is a rear view of FIG. 1 thereof.

FIG. 4 is a left side view of FIG. 1 thereof.

FIG. 5 is a right view of FIG. 1 thereof.

FIG. 6 is a top view of FIG. 1 thereof.

FIG. 7 is a bottom view of FIG. 1 thereof.

FIG. 8 is a top front perspective view of a second embodiment of a projector.

FIG. 9 is a front view of FIG. 8 of the design.

FIG. 10 is a rear view of FIG. 8 thereof.

FIG. 11 is a left side view of FIG. 8 thereof.

FIG. 12 is a right view of FIG. 8 thereof.

FIG. 13 is a top view of FIG. 8 thereof; and, FIG. 14 is a bottom view of FIG. 8 thereof.

The features shown in broken lines depict environmental subject matter only and form no part of the claimed design. The specification also includes an Appendix.
